VACUUM CLEANER

William J. Clements, Chicago, Ill., assignor to
 Clements Mfg. Co., Chicago, Ill., a corporation
 of Illinois

Application June 29, 1931. Serial No. 547,508

3 Claims. (Cl. 15—8)

My invention relates to an improvement in vacuum cleaners and has for one purpose the provision of a vacuum cleaner having an improved suction nozzle. Another object is to provide a cleaner particularly adapted to beating or sweeping a carpet while the carpet is suctionally upwardly drawn from the floor surface. Another object is the provision of means for preventing complete sealing of the carpet against the edges of the suction inlet or nozzle. Other objects will appear in the course of the specification and claims.

I illustrate my invention more or less diagrammatically in the accompanying drawing, 15 wherein

Figure 1 is a side elevation;

Figure 2 is a section on an enlarged scale along the line 2—2 of Figure 1;

Figure 3 is a view from below of the suction 20 nozzle illustrating the parts shown in Figure 2;

Figure 4 is a section along the line 4—4 of Figure 2; and

Figure 5 is a section along the line 5—5 of Figure 2.

25 Referring to the drawing, A generally indicates a motor housing in which any suitable motor, not herein shown in detail may be positioned. It is diagrammatically shown in dotted line as at A¹ in Figure 1.

30 B generally indicates a fan casing which may be screwed to or otherwise secured to one of the motor casings, as by the screws B¹. It is provided with an exhaust outlet B² to which may be secured any suitable dirt receiving bag B³ of air pervious material.

35 The forward face of the fan chamber or housing B is apertured to receive the suction inlet structure generally indicated as C. It may include a projection C¹ extending forwardly from the fan casing, and a nozzle structure C³ connected with the member C¹ as by the neck C². The nozzle proper, C³, is herein shown as terminating in a generally horizontal lower lip on the edge C⁴. The shape of this lip or edge may be 45 widely varied but may conveniently be made to lie in a single horizontal plane.

40 In order to support the vacuum cleaner movably upon the floor surface I may employ rollers or wheels D mounted for rotation about axes fixed in relation to the fan chamber B. I may mount them for example upon the abutments D¹. In the form herein shown I illustrate a rear supporting roller D² rotatably mounted upon the adjustment link D³, which in turn is rotatably mounted as at D⁴ upon a bracket D⁵ extending

rearwardly from the motor housing A. D⁶ indicates any suitable adjusting screw with the finger piece D⁷, whereby the link D³ may be rotated to adjust the height of the roller D² and thus to adjust the height of the lip C⁴ of the nozzle C³. I have illustrated the structure above described as a ready means for adjusting the height of the nozzle. It will be realized that other suitable means might be employed.

45 Rotatably mounted within the nozzle C³ is a brush body E with the bristles E¹, herein shown as spirally arranged about the brush body. E² indicates a pulley about which passes the driving belt E³. E⁴ is a driving pulley, about which passes the upper bend of the belt E³. It may 50 be mounted upon the extension shaft E⁵ which extends forwardly from the fan B⁴ and rotates in unison therewith in response to rotation of the rotor of the motor A¹. E⁶ are bearing brackets for the bearings E⁷ for the opposite ends of the brush body E, which receive the terminal ends E⁸ of the shaft or shafts upon which the brush body E is mounted.

55 G indicates a guard structure including the side members G¹ and the transversal arcuate members G². I illustrate three of these members G² as aligned with the pulley E², to prevent the carpet J from being sucked against pulley and belt. I may employ any suitable means for supporting the guard member in the position 60 shown in the drawing. I show for example a plurality of fixed inwardly projecting studs or lugs G³ and one or more removable supporting means G⁴ herein shown as a set screw. Longitudinal movement of the guard is prevented as 65 by the members G⁵.

70 Rotatably mounted at the ends of the nozzle C³ are the rollers H which may be mounted for example upon shafts H¹ extending between the ends of the nozzle and the intermediate brackets H². The rollers are preferably freely rotatable 75 in response to frictional contact with the carpet, to prevent wear. Preferably the lowest portion of the roller extends downwardly below the lower edge or lip C⁴ of the nozzle. Under some circumstances it will be desirable or at least practical to have the rollers H engage the carpet J when it is on the supporting surface. However, I prefer to space the rollers H somewhat 80 above the supporting surface. In either case 85 the result is to provide positive means for breaking the seal between the carpet and the lower edge of the nozzle which would otherwise result from the application of the suction to the carpet. As shown for example in Figures 2 and 90

100

105

110

4. the suction exerted by the fan B⁴ sucks the carpet upwardly toward the brush body E. Its upward movement is limited by the lip C⁴ and also by the transversal guard members G².
- 5 Where the carpet is so sealed against the movement, the air is first sucked downwardly through the carpet at a point exterior to the nozzle, and is then sucked upwardly through the carpet into the nozzle. I find it desirable to cause a flow of air across the upper surface of the carpet, between the carpet and the edge of the nozzle, and to break the seal between nozzle and carpet. I may employ any suitable means for breaking this seal, but I illustrate the rollers herein shown as a convenient means of obtaining my desired result. The air rushes in above the carpet at the ends of the nozzle to scour across the top of the carpet. This provides a ready means for picking up small particles, such as bits of thread, which would otherwise have difficulty in passing beneath the edge of the nozzle when such edge is in sealed relation with the carpet or rug.
- It will be noted also that the arcuate guards G² constrain the carpet to a more or less arcuate shape, across the arc of which the tips of the bristles of the brush sweep. While the arc of the members G² need not be made precisely concentric with the arc described by the bristle tips, none the less the arcuate disposition of the carpet increases the acceleration of the brushing action.

It will be realized that whereas I have described and shown a practical and operative device, nevertheless many changes may be made in size, shape, number and disposition of parts without departing from the spirit of my invention. I, therefore, wish my description and drawing to be taken as in a broad sense illustrative or diagrammatic, rather than as limiting me to my precise showing herein. The present application is a continuation in part of co-pending application 468,313, filed on July 16, 1930.

I claim:

- 45 1. In a vacuum cleaner, a motor and a housing therefor, a fan actuated by said motor and a fan chamber therefor having an air inlet passage and air outlet passage, a suction nozzle associated with said inlet passage and means for maintaining the lower edges of said suction nozzle spaced upwardly from the surface to be

cleaned, a brush rotatably positioned within said suction nozzle, means for rotating it in response to rotation of the motor, and means for breaking the sealing relationship between a carpet and both edges of the nozzle at the ends of the nozzle only otherwise resulting from the suction caused by rotation of the fan, including members downwardly projecting below the edge of the nozzle, such members terminating above the normal floor level, and being spaced laterally inwardly from the edge of the nozzle and the ends of the nozzle, whereby air may flow between the said members and the opposed portions of the nozzle edge.

2. In a vacuum cleaner, a motor and a housing therefor, a fan actuated by said motor and a fan chamber therefor having an air inlet passage and an air outlet passage, a suction nozzle associated with said inlet passage and means for maintaining the lower edges of said suction nozzle spaced upwardly from the surface to be cleaned, a brush rotatably positioned within said suction nozzle, means for rotating it in response to rotation of the motor, and means for breaking the sealing relationship between a carpet and the edges of the nozzle otherwise resulting from the suction caused by rotation of the fan, including rollers positioned at the ends of the nozzle, said rollers extending downwardly below the plane of the nozzle and being spaced upwardly from the floor.

3. In a vacuum cleaner, a motor and a housing therefor, a fan actuated by said motor and a fan chamber therefor having an air inlet passage and air outlet passage, a suction nozzle associated with said inlet passage and means for maintaining the lower edges of said suction nozzle spaced upwardly from the surface to be cleaned, a brush rotatably positioned within said suction nozzle, and means for rotating it in response to rotation of the motor, and means for breaking the sealing relationship between a carpet and the edges of the nozzle otherwise resulting from the suction caused by rotation of the fan, including rollers rotatably mounted within and adjacent the ends of the nozzle said rollers extending downwardly below the plane of the nozzle and being spaced upwardly from the floor.
